WEATHER STRIP

Application filed February 8, 1929. Serial No. 338,488.

This invention relates to metal weather strips particularly adapted for the windows of buildings, the principal object being to provide a more practical and readily assembled weather strip than heretofore known.

Other objects and advantages of the invention will appear in the following description thereof.

Referring now to the accompanying drawing, forming part of this application, the same represents a horizontal section through one side of a common window frame showing the two sashes opposite each other.

1 represents the outermost or upper sash of the window, and 2 the innermost or lower sash, while 3 represents the frame, 4 the parting strip, 5 the inner stop, and 6 the outer stop.

The weather strips for both sashes are substantially identical, though we have shown the one for the outer sash slightly differing in that the major portion is not cooperatively connected with the parting strip of the window.

25 We will first describe the weather strip as applied to the innermost or lower sash, the major member of which strip comprises that portion 7 which lies against the frame entirely covering the sashway, and preferably extending sufficiently beyond same to be slightly overlapped by the inner stop 5, thus providing sufficient room for securely fastening same as by nails indicated at 8 externally of the sash 2.

35 The minor member of the weather strip comprises the U-shaped interlocking portion 9 and the flange-like portion 10, the latter providing means for nailed engagement with the sash as at 11, and the U-shaped portion 40 nesting within the scarfed or recessed outermost corner 12 of the sash.

The cooperative engaging portion of the major member of the weather strip is accomplished by forming a three fold groove 45 therein, that is to say the edge of the member is folded backwardly upon itself at three different points, forming a groove between the spaced folds thereof, and terminating in a laterally extending comparatively narrow flange 13, oppositely disposed to the

portion 7 thereof, but in the same plane. This narrow flange is designed to be let into the parting strip 4 by first forming in the parting strip a kerf therefor, and one of the advantages of our present invention is that this kerfing may be done to both the parting strip and outer stop while in place in the window frame or of course the former may be removed for such purpose if desired. While we have shown the flanged portion 55 of the minor member as not being let into the sash and it appearing relatively thick, it is to be understood that it also may be stepped into the sash if desired, and particularly so if the fit of the sash happens to be tight.

60 The weather strip for the outer or uppermost sash is identical in form to that just described for the inner sash 2 except that we prefer to avoid the necessity of kerfing the outer side of the parting strip but instead to kerf the inner face of the outer stop 6, as at 14, for the reception of the extreme outermost edge of the body portion 16 of the major member of the weather strip; it being of like width to the portion 7 of the inner sash 65 weather strip. This portion 15 may be additionally secured as by nails indicated at 16 to the window frame, the inner edge of this portion of the outer weather strip not being kerfed into the parting strip, and in this respect only differing from the weather strip 70 for the innermost sash 2.

75 The minor member 17 of this window weather strip is identical with that previously described for the inner sash, and is nailed 80 to the sash 1 as by the nails 18; the cooperative tongue and groove arrangement of members being identical.

85 From the foregoing it is evident that the installation of the weather strips may be accomplished as follows:

90 First the stop 5 is removed, then the sash 2, the parting strip 4 and the sash 1 are removed. Then the outermost stop 6 may be kerfed as at 14, the innermost corner of the sash 1 scarfed, and the minor member 17 of the weather strip fastened therewithin, when the major member 15 may be cooperatively united therewith and the sash replaced, forcing the edge of the major member 15 into the 95 100

kerf in the outer stop, when of course this may be additionally nailed by sliding the sash up or down, providing access thereto. Then the parting strip 4 may be reinstalled, either kerfed prior to such reinstallation or thereafter as desired. Then the outermost corner of the inner sash 2 is scarfed, the minor member of the weather strip installed together with the placing of the major member therein, when the sash may be replaced, forcing the minor flanged portion 13 into the kerfed parting strip, and the major member additionally secured by the nails 8, when finally the inner stop 5 is placed in position, thus making an entirely novel form of weather strip installation and one exceptionally efficient in that both major members of the strips are kerfed into the stops of the window.

Having thus described our invention, what we claim and desire to secure by Letters Patent, is:

Metal weather stripping for windows having two slidable sashes therein, outer and inner stops and a parting strip, comprising interengaged metal strips for each sash adjacent the parting strip, characterized by one member of each pair of strips completely covering the sashway and terminating adjacent the parting strip in double closed folds and the other member of each pair comprising an open U-shaped fold for cooperative engagement with the double closed folds of the other members.

In testimony whereof we affix our signatures:

ARNOLD J. SPANJERS.
ANTON R. P. SPANJERS.
